UNITED STATES PATENT OFFICE.

AUGUST J. KREUZKAMP, OF CHICAGO, ILLINOIS, ASSIGNOR TO ENGLANDER SPRING BED COMPANY, OF BROOKLYN, NEW YORK.

COMBINED KNOCKDOWN SLIDING COUCH OR BED.

1,368,510.

Specification of Letters Patent. Patented Feb. 15, 1921.

Application filed August 2, 1917. Serial No. 184,123.

To all whom it may concern:

Be it known that I, AUGUST J. KREUZKAMP, a citizen of the United States, residing at Chicago, in the county of Cook and State of Illinois, have invented certain new and useful Improvements in Combined Knockdown Sliding Couches or Beds, of which the following is a specification.

This invention relates to an improvement 10 in beds or couch beds, the object of the invention being to provide a combined knockdown bed comprising a main section or bed consisting of a head, a foot and a bed bottom or spring mattress section detachably connected to the head and foot in such a manner 15 that the spring mattress section may be readily disconnected or connected with the head and foot, and a shiftable or sliding section shiftable relatively to the spring mattress section of the main section whereby 20 when it is desired to knock down the structure for shipping or storing purposes, both spring mattresses may be detached from the head and foot of the main section while at 25 the same time the structure can be used either as a single bed or couch or as a double bed.

It is an object of the invention to accomplish the foregoing by the provision of a structure which is simple in its construction, 30 durable and rigid in use and which at the same time is comparatively inexpensive to manufacture.

Sliding couch beds with which I am familiar usually comprise a main section and 35 a sliding section, the main section consisting of a spring mattress permanently connected with the head and foot, so that it is not practical for the user to disconnect the spring fabric from the head and foot in any ordinary way to permit the two spring fabrics 40 to be disassembled from the head and foot for storage or other purposes and consequently it has been the practice to build the main section of the sliding couch bed with as 45 small a head and foot as is possible thereby to decrease the weight of structure, since such a bed provided with a fair sized head and foot would be too heavy to handle or to manipulate.

50 In the present improvement, however, by reason of the fact that both spring fabrics may be readily detached from the head and foot, the bed may be made up of a suitable ornamental head and foot of any desired size 55 or style, since as the spring mattresses can

both be removed therefrom, the handling of the structure is very much simplified and the weight of the head and foot is no longer a material factor to be considered.

In short, the object of the present improvement is to provide a sliding couch bed which will have more the appearance of an ordinary bed and less of the appearance of the ordinary couch without, however, increasing the weight of the structure necessary to be 60 handled by the user when it is desired to assemble the article.

In the drawings accompanying and forming a part of this specification,

Figure 1 is a perspective view partly 70 broken away of this improved bed illustrating the structure when the sliding section is extended; Fig. 2 is a partly cross-sectional view of Fig. 1 with the springs and soft mattress omitted; Fig. 3 is a similar view to 75 Fig. 2 but showing the bed closed; Fig. 4 is a sectional view taken on line 4—4 Fig. 3; Fig. 5 is a sectional view on line 5—5 of Fig. 4; Fig. 6 is a detail perspective view of one corner of the main section; Fig. 7 is a detail 80 view of one corner of this improved bed when the sections are closed; and Fig. 8 is a detail of the fastening or hook for detachably securing the spring mattress to the head and foot of the main section.

Similar characters of reference indicate 85 corresponding parts in the several figures of the drawings.

This improved bed comprises a main section 1, and a sliding supplemental section 20. 90 The main section comprises a head 2 and a foot 3, each of which in the present instance consists of a pair of legs 4 connected by cross members 5 and 5', which in turn are suitably connected by uprights or posts 5² thereby 95 forming the head and the foot usually made of tubular material of some suitable size. Each leg is provided on its inner side at a predetermined distance below the top spring with inwardly extended headed pins 6 and 100 at a point adjacent to the top of the spring with a swinging hook 7, each pivotally secured to its leg on the inside. The spring mattress frame or section comprises a pair 105 of end members 8, to which a spring fabric 9 is connected in the usual manner, and each of these end members shown in the present instance as formed of angle iron is provided with a depending portion 10, the depending portions on each side being suitably con- 110

nected by a side bar 11 for maintaining the ends properly spaced apart when the spring fabric is stretched therebetween. Each of these depending ends is provided with a 5 notch or slot 12 at its lower end for the reception of the headed pins hereinbefore referred to carried by the legs of the head and foot.

As the pivotally connected swinging hooks 10 carried at each side of the head and foot extend over or into the framework forming the main mattress section comprising the side bars and cross bars to which the spring fabric is permanently connected and 15 between which cross bars the fabric is stretched, these hooks act to wedge this main mattress section into tight engagement with the head and foot and so prevent any shaking or wobbling joints, while at the same 20 time on first releasing the hooks the lower pin and notch connections act as pivots thereby to permit the head and foot to be swung away from the main mattress section and its sliding section or outward so that it 25 is unnecessary to maintain the head and foot in parallel relation with each other or with the ends of the mattress sections in order to permit the ready detachment of the head and foot from said mattress sections. 30 From the foregoing it will be observed that the detachable mattress section of the main section of the bed is connected with the head and foot at the bottom thereof relatively remote from the top by simple pin 35 and slot connections and at the top by the swinging hooks 7, which hook over the cross angle bars of the bed bottom or mattress section and which bed bottom of course can be formed of any suitable material as metal 40 or otherwise, whereby on raising the hooks the detachable spring mattress section can be readily released from its pins by slightly swinging the head and foot and lifting each end from the head and foot respectively. 45 By means of the present improvement, one mattress section can be readily interchanged with the head and foot of another without being specially fitted thereto, whereas it is usually necessary that the spring mattress 50 be specially fitted to its head and foot as they are not interchangeable.

In the present improvement, the spring mattress section is connected with the head and foot by two entirely different kinds of 55 connection, one of which is releasable prior to the other and one of which in the present instance is shown as a pin and slot connection, and the other of which is shown as a shiftable or swinging hook connection 60 whereby on the mere lifting of the hook the spring mattress section or the spring mattress supports or side bars which carry such spring mattress may be readily detached from the foot and head without the necessity 65 of maintaining the head or the foot, as the

case may be, and the spring mattress section in parallel juxtaposition so as to enable the mattress section to be slid upward and then removed. In other words, in the present improvement it will be observed that by 70 merely first releasing or swinging the hook 7 away from the cross angle bars 8, the head or foot can be swung away from the mattress section to facilitate the lifting of the latter from the pins 6, whereas if a pin and slot connection similar to that shown at 6 75 were substituted for the hook shown at 7, the result would be that in order to lift the mattress section, it would be necessary to slide the mattress section upwardly relatively to 80 the head or the foot while maintaining the head and foot in parallel relation with the end of the mattress section—a rather difficult thing for one person to do with a heavy structure of this kind, especially as such pin 85 and slot connections frequently stick or bind.

In the present improvement however, the hooks are shifted before the mattress section is handled and then the head or foot can be 90 swung away from the mattress section so that it is not necessary to maintain it in parallel relation with the end of the mattress section in order to disconnect the pin and notch connection, and this swinging 95 movement of the head or foot tends to loosen the pin and notch connection and so relieve any binding or sticking action at this point, so that the mattress can be readily and easily lifted. In ordinary bedsteads, the head and 100 foot are usually connected by side bars upon which is placed the spring mattress comprising a suitable framework, also including side bars for maintaining the fabric stretched when the mattress is removed from 105 the bed structure.

In the present improvement however, it will be observed that the head and foot are unprovided with side bars, the only side bars used being those forming a part of the 110 spring mattress section, the location of which relatively to the mattress being such that the spring mattress section maintains the head and foot rigidly in position. Thus the cost of the structure is materially lessened since a pair of side bars are done away with.

Located between the head and foot and carried by the side bars of the main mattress section are a pair of cross angle bars 120 15 having tracks, each provided with a curved portion at one end as 16, to limit the movement of the rollers about to be described. The supplemental or sliding section 20 comprises two end frames 21 and 22, 125 each comprising a cross bar 23 and a leg 24, the legs being connected by a side bar 25 and suitably braced as at 26. Stretched between the end frames is a metallic fabric or spring mattress or other suitable bed bottom 130

27 and this spring mattress is located between the side bar and the spring fabric or mattress of the main section. The inner side of this sliding section is provided with 5 a pair of depending members 28 likewise connected by a lengthwise extending bar 29 and to these depending members is connected a pair of rollers supported on the upwardly curved ends of the tracks hereinbefore referred to, constituting a means for sufficiently raising the inner side of the sliding section into substantial alinement with the main section so that the two spring fabrics will be practically level as well as 10 15 a means for somewhat limiting movement of the sliding section when extended.

From the foregoing it will be observed that the present improvement comprises two mattress sections, one sliding relatively to 20 the other, that is, one sliding between the side bar and the fabric of one mattress section and that both mattress sections are detachable or removable from the head and foot of the main section, either separately 25 or together as occasion may require, while the unitary sliding section is supported by the head and foot through the unitary main mattress section.

It will of course be understood that the 30 various details may be more or less changed without departing from the spirit or scope of the present improvement.

I claim as my invention:

1. A knock-down bed structure comprising 35 a head and a foot and a pair of spring mattress sections, one a main section and the other a sliding section, both detachably supported by the head and foot, the sliding section through the medium of the main 40 mattress section, the sliding section having shiftable movement relatively to the main section thereby to form a double bed.

2. A knock-down bed structure comprising 45 a head and a foot and a pair of spring mattress sections, one a main section and the other a sliding section, both detachably supported by the head and foot, the sliding section through the medium of the main mattress section, the sliding section having shif-

able movement relatively to the main section 50 thereby to form a double bed, and said sliding section also being detachable from said main section.

3. A knock-down bed structure comprising 55 a head and a foot, and a pair of spring mattress sections, one a main section and the other a sliding section, both detachably supported by the head and foot, the sliding section through the medium of the main mattress section, the sliding section having 60 shiftable movement relatively to the main section thereby to form a double bed, the sliding section having a pair of legs at its outer side and a pair of rollers at its inner side and the main section having a pair of 65 tracks for the reception of said rollers.

4. A knock-down bed structure comprising 70 a head and a foot, and a pair of spring mattress sections, one a main section and the other a sliding section, both detachably supported by the head and foot, the sliding section through the medium of the main mattress section, the sliding section having shiftable movement relatively to the main section 75 thereby to form a double bed, the sliding section having a pair of legs at its outer side and a pair of rollers at its inner side and the main section having a pair of tracks for the reception of said rollers and the main section having side bars between which and 80 its fabric the fabric of the sliding section is located.

5. A knock-down bed structure comprising 85 a head and a foot and a main mattress section including a stretched fabric detachably supported by said head and foot, and a sliding section likewise including a stretched fabric and shiftable relatively to the fabric of the main section one under the other to 90 form a single or a double bed and supported by the head and foot through the medium solely of the main section.

Signed at Chicago, Illinois, this 30th day of July, 1917.

AUGUST J. KREUZKAMP.
